REMOTE POWERED CULINARY BEATER HEAD

Joseph R. Corbett, Cincinnati, Ohio

Application December 31, 1953, Serial No. 28,293

Term of patent 14 years

(Cl. D44—1)

To all whom it may concern:

Be it known that I, Joseph R. Corbett, a citizen of the United States, residing at Cincinnati, in the county of Hamilton and State of Ohio, have invented a new, original, and ornamental Design for a Remote Powered Culinary Beater Head, of which the following is a specification, reference being had to the accompanying drawing, forming a part thereof.

Figure 1 is a perspective view of a remote powered culinary beater head showing my new design.

Figure 2 is a front elevational view thereof.

Figure 3 is a side elevational view thereof.

I claim:

The ornamental design for a remote powered culinary beater head, substantially as shown.
